HAT FLANGING MACHINE

Filed Feb. 18, 1929

Fig. 1.

By Clarence A. O'Brien, Attorney

UNITED STATES PATENT OFFICE

CHARLES HYMAN BAUMWELL, OF COLORADO SPRINGS, COLORADO

HAT-FLANGING MACHINE

Application filed February 18, 1929. Serial No. 341,012.

This invention relates to a machine for forming a flange or brim upon a hat, by subjecting the flange to pressure and heat and steam so that the brim has the proper final set or curl.

A primary object of this invention is to provide a machine of the character set forth whereby the four essential elements entering into the operation of hat flanging will be provided, namely, pressure, moisture, steam and heat. In the ordinary sand bags used today in machines of this type there is but one of these elements present, namely, pressure, which pressure is supplied by its own weight. 10 Heat is supplied to the bag by letting it rest on a steam chest, or a horizontal steam radiator, while not in use; while the other two elements, steam and moisture are supplied by ironing or steaming the hat brim previous 15 to sand bagging.

A still further object of my invention is to provide a machine of the character set forth embodying these four essential elements, which will be easy to operate, of a 20 compact structure which will save much time and labor, and otherwise well adapted for the purpose designed.

Further objects and advantages of my invention will become readily apparent from 25 time to time during a study of the following description taken in connection with the accompanying drawings, wherein:

Figure 1 is a side elevation.

Figure 2 a transverse section on line 2—2 30 of Figure 1, and

Figure 3 a vertical section on line 3—3 of Figure 2.

When reference is had to the drawing, and especially to Figure 1, it will be seen that the 40 hat flanging machine illustrated therein embodies a work table 5 upon which is suitably supported by means of brackets 6 a former which is generally designated as at 7, the same being held in spaced relation to the top surface 45 of the table 5 as shown in Figure 1.

Disposed upon the top surface of the table 5 and in alinement with the former 7 is a platform 8 from which a rack gear 9 depends centrally through the table for reciprocation within a guide 10 which is suitably fastened 50 to the undersurface of the table. The guide 10 is provided with an opening 10' to permit the gear 9 to mesh with a semi-circular gear 11 mounted on a shaft 12 journaled in a bracket 13 carried by the undersurface of the 55 table. Mounted on the shaft 12 is a hand operating lever 14 for operating the gears to raise or lower the platform 8. Suitably supported on the platform 8 is a conventional die 15 for movement into or out of 60 contact with the former 7 when the platform is raised or lowered by operation of the hand lever 14.

Attention is now directed to Figure 3 wherein the construction of the former 65 is more clearly illustrated. As herein shown, the former comprises an outer metallic, cylindrical shape enclosure 15, the rim of which is corniced as at 16 to provide a box-like structure 17 entirely around the rim. A 70 metallic netting 18 is laid around the opening of the box 17 as is clearly shown in Figure 3 of the drawing. The purpose of so constructing the cylindrical member 15 will be hereinafter set forth. An additional cylindrical member 19 is nested within the member 15 and is securely welded thereto as at 20. This member 19 is of smaller dimension than that of the first mentioned cylinder 15 and maintains an equal space from the member 15 75 over its entire surface. The cylindrical member 19 comprises spaced walls A and B, each of which walls is perforated as at 19'. These perforations are in alinement and are connected by means of a tube 32 as clearly shown in Figure 3 of the drawing. A cloth preferably of heavy flannel or like material 21, is secured at its edges to the cylindrical member 15 and is held in place thereto by a metal draw band 22 as clearly shown in Figure 3 80

85

90

of the drawing. A filling tube 23 extends through the top of the cylindrical members 15 and 19, and is open at its lower end while the upper end is closed by a hinged cover 24. 5 By means of the tube 23 small metallic sphericals of about the size of buck shot may be introduced into the former. The space between the cylindrical members 15 and 19 constitutes a steam space to which live steam is 10 applied by means of a perforated pipe 25 disposed within the box like housing 17, suitably connected to an inlet pipe 26 communicating with a steam supply source, not shown.

If desired, steam may be delivered in the 15 space between the walls A and B of the cylinder 19 by operation of the valve 33' on the steam pipe 33, which pipe leads from a suitable source of steam supply into the lower portion of the cylinder 19 as at 34. By letting 20 steam into this space a heat chamber is provided which can be kept hot continuously, independently of the rest of the structure. Consequently the former is thus kept hot when the machine is idling, that is, when the 25 operator may be busied with other work, noon hour, etc.

Another important feature of this auxiliary heat chamber is that the steam which permeates through the space between the cylinders 15 and 19 is purified and its dampness taken up by the heat in the auxiliary chamber, thus permitting pure dry steam to flow on to the hat.

In operation of the device, a hat either 35 of felt, straw, panama, leghorn, or the like is placed upon the die 15 as shown in Figure 3 of the drawing. By operating the handle 14 the gears 9 and 11 intermesh and raise the platform 8 to elevate the die for contact 40 with the cloth 21 of the former. The handle 14 is operated until the former and die assume a position as shown in Figure 3 of the drawings. By operation of the valve 27 which is connected by a chain 28 to a pedal 45 29 pivotally mounted on the floor as at 30 steam may be continuously or intermittently delivered to the perforated pipe 25 to permeate through the space formed between the cylinders 15 and 19, said steam then forcing 50 its way through the tubes 32 formed on the inner cylinder. The steam then distributes itself to the mass of metal balls onto the hat. The hat being cool upon receiving the steam turns it into moisture and the brim becomes 55 pliable. When in this condition under the pressure of the hot metal the hat brim begins to take the shape of the die, and then by releasing the pedal 30 the steam is shut off, and the heat within the former then draws out the 60 moisture from the brim. The hat form is then lowered and the hat removed and allowed to cool off while the operator may take up the next hat and treat it in the manner above set forth.

65 It is readily seen that in using this ma-

chine wet ironing and steaming may be dispensed with, as the former contains the live steam within itself and the metal filler used instead of sand will more evenly distribute itself over the hat by gravity to provide an 70 ironing means.

It is yet to be mentioned that any accumulation of water within the pipe 25 will be forced into the box-like structure 17 which will act as a water duct and may be drained 75 through the outlet 31. As an additional water arresting measure, a metal netting is laid around the opening of the box like structure 17, as before described, which permits free flow to the steam while the water if any is 80 trapped and sent through the water duct to the outlet.

From the foregoing therefore it will be seen that I have provided a machine for flanging hats wherein the four essential elements necessary in pressing hats are contained, viz, pressure, heat, moisture, and steam, and whereby all of such elements may be applied in a minimum amount of time. 85

Having thus described the invention, what I claim as new and desire to secure by Letters Patent is:—

1. In a hat flanging machine of the class described, a former comprising a pair of spaced cylinders, one disposed within the other, a perforated pipe located between said cylinders for supplying steam to the former, manually operated valve means for controlling the passage of steam into said pipe, a metal netting disposed between said cylinders and above said perforated pipe, a flexible sheet depending from said cylinders, means extending through said cylinders to permit the introduction of spherical heat retaining elements into said former, a die, a manually controlled operating means for moving the die into and out of contact with said former. 95

2. In a hat flanging machine of the class described, a former comprising spaced cylinders, one disposed within the other, manually operated valve control means for supplying steam to said former, a flexible bottom provided on the former, metallic sphericals carried in the former and resting upon said flexible bottom, supporting means for the former, and a vertically reciprocating die carried by said support and adapted for contact with said former. 110

3. In a hat flanging machine of the class described, a former comprising a pair of spaced cylinders, one disposed within the other, means for supplying heat to the space between said cylinders, a metallic netting disposed within the space and carried by the cylinders to provide a water trap, a flexible sheet depending from the cylinders, and metallic sphericals within said sheet to provide heat retaining and distributing means for the former. 115

4. In a hat flanging machine of the class described, a former comprising a pair of spaced cylinders, one disposed within the other, the inner cylinder comprising spaced walls, perforations formed on each of said spaced walls, said perforations being in alignment, tubes connecting the aligned perforations, means for supplying steam into the space between the cylinders, means for supplying steam between the spaced walls of the inner cylinder, a flexible sheet depending from the outer cylinder, and heat radiating material within said sheet.
